UNITED STATES PATENT OFFICE.

BRYAN BURFORD PYLE AND HOMER RALPH COMPTON, OF SEMINOLE, OKLAHOMA.

WRENCH.

Application filed November 21, 1927. Serial No. 234,829.

The present invention relates generally to wrenches and more particularly to a wire rope twister. In well drilling operations it is necessary to twist the wire rope and this is usually done with an ordinary pipe wrench which from time to time accidentally slips out of the workman's hand and flies around and injures him and sometimes flies off the rope and becomes lost in the well.

10 The principal object of the present invention is to provide a wrench which overcomes these annoyances.

A still further important object of the invention resides in the provision of a wrench of this nature which is exceedingly simple in its construction, strong and durable, inexpensive to manufacture, thoroughly efficient and reliable in use, and otherwise well adapted to the purpose for which it is 20 designed.

With the above and numerous other objects in view as will appear as the description proceeds, the invention resides in certain novel features of construction, and in 25 the combination and arrangement of parts as will be hereafter more fully described and claimed.

In the drawings:

Figure 1 is a top plan view of the wrench embodying the features of my invention,

Figure 2 is a sectional view therethrough taken substantially on the line 2—2 of Figure 1,

Figure 3 is a detail elevation of the cam lever,

Figure 4 is a sectional view taken substantially on the line 4—4 of Figure 1,

Figure 5 is a plan view of another embodiment of the wrench, and

40 Figure 6 is an elevation of the sucker rod upon which the modified form of the wrench may be used to advantage.

Referring to the drawing in detail it will be seen that the numeral 5 denotes a U-shaped body having transverse passages 6 in the legs thereof adjacent the bight thereof for slidably receiving the jaw 7 or a jaw 7' the former being shown in Figure 1 and the latter being shown in Figure 5. Spokes 8 extend diagonally from the body 5 and a split rim 9 is formed on the ends thereof. The space caused by the split in the rim being coincident with the space between the legs of the body 5 thereby forming an en-

trance for a wire rope in the embodiment 55 shown in Figure 1 and for a sucker rod 10 for the embodiment shown in Figure 5. The jaw 7 and the jaw 7' each is formed with an extension 11 having an elongated longitudinal slot 12 therein. The numeral 60 13 denotes a lever having a cam end 14 with openings to receive a pin 15. The cam end 14 is bifurcated to straddle the extension 11 and the pin 15 extends through the slot 14. A set screw 16 is threaded through the end 65 of the shank 11 into the slot 12 to bear against the pin 15 for adjusting the jaw 7 and the jaw 7'. The jaw 7 is provided with serrations 17 and the body with serrations 18 in the embodiment shown 70 in Figure 1 so that when the lever is in the position shown in Figure 1 the serrations will bite into the wire rope so that the same may be readily twisted. It will be seen that if the rim 9 twists out of the operator's 75 hand no injury will be occasioned and the wrench will not become lost. A bolt 20 projects from the jaw 7 and the jaw 7' opposite to the shank 11 and impinges against the body 5 and against a nut 21 on the bolt 80 20, said spring being denoted by numeral 22. This spring will move the jaw when the lever 13 is swung to a position from that shown in Figure 1 as will be quite apparent for releasing the cable. The jaw 7' is made 85 to engage a sucker rod of the square end 10' thereof. If desired the jaw 7' may be removed with the cooperating parts and the sucker rod placed in the body 5; in order to prevent it from accidentally coming out 90 a spring pressed ball 25 is provided in one leg of the body 5, the spring being denoted by the numeral 26 and a tensioning screw being denoted by the numeral 27.

It is thought that the construction, operation, utility, and advantages of this invention will now be quite apparent to those skilled in this art without a more detailed description thereof. The present embodiment of the invention has been disclosed in 95 detail merely by way of example since in actual practice it attains the features of advantage enumerated as desirable in the statement of the invention and the above description. It will be apparent that changes in 100 the details of construction and in the combination and arrangement of parts may be resorted to without departing from the 105

spirit or scope of the invention as herein-after claimed or sacrificing any of its advantages.

Having thus described our invention, what we claimed as new is:

1. In a wrench of the class described, a U-shaped body with spokes projecting therefrom, a split rim formed on the end of the spokes extending from the terminal of one leg of the body to the terminal of the other leg thereof about the bite portion thereof, said body being provided with a transverse passage, a movable jaw in the transverse passage and a cam lever pivotally engaged on the jaw and operable against the body.
- 10 2. In a wrench of the class described, a

U-shaped body with spokes projecting therefrom, a split rim formed on the end of the spokes extending from the terminal of one leg of the body to the terminal of the other leg thereof about the bite portion thereof, 20 said body being provided with a transverse passage, a movable jaw in the transverse passage and a cam lever pivotally engaged on the jaw and operable against the body, 25 spring means associated with the movable jaw for normally holding the same open.

In testimony whereof we affix our signatures.

BRYAN BURFORD PYLE.
HOMER RALPH COMPTON.
